UNITED STATES PATENT OFFICE.

FRIEDRICH BERNHARD UEBEL, OF PLAUE, GERMANY, ASSIGNOR TO
THE FIRM OF GEBRÜDER UEBEL, OF PLAUE, GERMANY.

COMPOUND FABRIC.

SPECIFICATION forming part of Letters Patent No. 761,051, dated May 24, 1904.

Application filed August 24, 1903. Serial No. 170,627. (Specimens.)

To all whom it may concern:

Be it known that I, FRIEDRICH BERNHARD UEBEL, a subject of the King of Saxony, whose post-office address is No. 19 Weststrasse, 5 Plauen, Vogtland, Kingdom of Saxony, German Empire, have invented a new and useful Compound Fabric, of which the following is a specification.

The article known in the trade as "spar-
terie" is composed of an upper textile made
in the form of matting and a support for the
same consisting of muslin, to which the former
is fastened by suitable agglutinants. Up to
this invention the said matting has been made
with strips of esparto, halfa, wood, or straw,
and owing to this mode of manufacture the
matting could be produced with a very lim-
ited size only. This limited size involves a
considerable waste in cutting the blanks for
figured articles; and it is the object of the
present invention to do away with this draw-
back.

To this end the present invention, as illus-
trated by six examples of executional forms
on the annexed sheet of drawings, consists in
a compound fabric composed of a textile layer
of the muslin type forming the base, support,
or backing *m* and a second textile made as a
matting with strips *t*, each of which is com-
posed by a number of individual threads ar-
ranged closely side by side at the upper part
of the support *m*, the matting being pasted to

the backing by means of a suitable aggluti-
nant. As those threads can be of any desired
length and even of unlimited length, the fabric 35
is enabled to be manufactured with a greater
breadth than heretofore and with any desired
length. The most important advantage of
this new fabric is that in using the same for
making figured articles—such as hats, bon- 40
nets, caps, and the like—the blanks are en-
abled to be cut with considerably less waste,
as projecting portions of one blank can be
placed in corresponding receding portions of
other blanks. 45

What I claim as my invention, and desire to
secure by Letters Patent, is—

As an article of manufacture a stiff com-
pound fabric consisting of two textiles pasted
together, of which the one, the backing *m* 50
consists of a textile layer of the muslin type,
and the other textile of a matting made with
strips *t* which are composed each of a num-
ber of individual threads arranged closely
side by side substantially as described and 55
for the purpose specified.

In testimony whereof I have hereunto set
my hand, in presence of two subscribing wit-
nesses, this 11th day of August, 1903.

FRIEDRICH BERNHARD UEBEL.
